UNITED STATES PATENT OFFICE.

LOUIS J. KORTER, OF PORT TOWNSEND, WASHINGTON.

GAME-CARRIER.

1,064,917.

Specification of Letters Patent. Patented June 17, 1913.

Application filed December 11, 1912. Serial No. 736,189.

To all whom it may concern:

Be it known that I, LOUIS J. KORTER, a citizen of the United States, residing at Port Townsend, in the county of Jefferson and State of Washington; have invented 5 certain new and useful Improvements in Game-Carriers, of which the following is a specification, reference being had to the accompanying drawings.

10 This invention relates to new and useful improvements in game carriers and more particularly to a device of this character constructed of wire or other similar material, the object of the invention being to provide a neat, strong and compact device 15 which is adapted to the carrying of game birds of various kinds and is so constructed that a large number of birds can be easily carried by the hand or suspended from the belt.

20 Another object of the invention is to provide a game carrier of this character which will possess advantages in points of efficiency and durability, is inexpensive to manufacture and at the same time is simple in construction and operation.

25 With the above and other objects in view, the invention consists in the novel features of construction and the combination and arrangement of parts hereinafter more fully described, pointed out in the claims and shown in the accompanying drawings, in which—

30 Figure 1 is an elevation of a game carrier constructed in accordance with my invention. Fig. 2 is a similar view showing the device in its closed position.

35 In carrying out my invention, I form the device of two sections 1 and 2. The section 40 2 is formed of a single length of wire bent at its intermediate portion to form two spaced parallel arms 3 and the intermediate portion of said wire is bent to form an open loop 4. The ends of the spaced parallel 45 portions 3 are looped to form the eyes 5.

40 The section 1 is formed of a single length of wire bent upon itself at its intermediate portion and the parallel portions thereof are bent to extend in opposite directions and 50 form the loop or finger hold 6. The parallel portions are then bowed in opposite directions to form the open loop 7, and the ends of the wire arranged in spaced parallel relation as shown at 8. The extreme ends of 55 said wire are bent upon themselves to form a suitable hook members 9 adapted to engage

with the eyes 5 so that the sections 1 and 2 may be pivotally connected together.

A hook member 11 is provided, one end of which is bent upon itself to form an eye 60 12 and is slidably mounted upon one of the side portions of the section 8. The other end of the member 11 is bent to form a hook 13 adapted to engage the other of the side portions of the section 8 to retain the side 65 portions thereof in close relation, the resiliency of the wire of which said sections are constructed being of such as to expand when the hook member is released to the position shown in Fig. 2.

70 In stringing game birds upon my improved carrier, the head of the bird is inserted through the open loop 7 and the neck of the bird is passed downwardly between the parallel portions 3 until the same reaches 75 the loop 4, the first bird strung upon the carrier being disposed within this loop. After the birds have been strung upon the carrier, the hook portion 12 of the member 11 is engaged with the opposite side portion 80 of the section 8 to prevent the removal of the heads of the birds between the parallel portions 3. In this manner it will be seen that any number of game birds may be easily strung upon the carrier and the carrier 85 may be easily carried by the hand or suspended from the belt.

When the device is not in use, the same is to be folded up in the position shown in Fig. 2, so that it may be easily carried in 90 the pocket or other small space.

It will be readily apparent from the above that I have provided a simple, durable and strong device which is especially adapted 95 for use by hunters, but may be readily used in market places for suspending chickens or other game birds for display.

100 While I have shown and described the preferred form of my invention, it will be obvious that various changes in the details of construction and in the proportions may be resorted to for successfully carrying my invention into practice without sacrificing any of the novel features or departing from the scope of the appended claim.

105 What I claim is:—

110 In a device of the character described, the combination of a single length of wire bent at its intermediate portion to form two spaced parallel portions, a second length of wire bent to form a finger loop and then bent to form an open loop arranged adja-

cent the finger loop, the ends of said second wire being disposed in spaced parallel relation and the extreme ends pivotally connected with the ends of the first wire, a hook member having one end bent to form an eye and pivotally mounted upon one of the parallel portions of the second wire and the other end of said hook member being bent to form a hook adapted to engage with

the other parallel portion to retain the device in a closed position.

In testimony whereof I hereunto affix my signature in the presence of two witnesses.

LOUIS J. KORTER.
